FIG. 1 is a front elevational view of a light standard or similar article illustrating my new design.

FIG. 2 is a side elevational view thereof.

FIG. 3 is a greatly enlarged cross-sectional view taken on line 3—3 of FIG. 1.

FIGS. 4 and 5 are greatly enlarged cross-sectional views of different embodiments of my design, taken on the planes of the respective embodiments identical to line 3—3 in FIG. 1, it being understood that these embodiments differ from FIG. 1 only in cross-section.

FIG. 6 is an enlarged front elevational view of a further embodiment of my design.

FIG. 7 is a greatly enlarged cross-sectional view taken on line 7—7 of FIG. 6.

FIG. 8 is a side elevational view thereof.

FIG. 9 is an enlarged front elevational view of a further embodiment of my design.

FIG. 10 is a side elevational view thereof.

FIG. 11 is an enlarged front elevational view of a further embodiment of my design.

FIG. 12 is a side elevational view thereof.

FIG. 13 is an enlarged front elevational view of a further embodiment of my design.

FIG. 14 is a side elevational view thereof.

FIG. 15 is an enlarged front elevational view of a further embodiment of my design.

FIG. 16 is a side elevational view thereof.

FIG. 17 is an enlarged front elevational view of a further embodiment of my design.

FIG. 18 is a side elevational view thereof.

FIG. 19 is an enlarged front elevational view of a further embodiment of my design.

FIG. 20 is a side elevational view thereof.

FIG. 21 is an enlarged front elevational view of a further embodiment of my design.

FIG. 22 is a side elevational view thereof.

FIG. 23 is a front elevational view of a further embodiment of my design.

FIG. 24 is a side elevational view thereof.

FIG. 25 is a front elevational view of a further embodiment of my design.

FIG. 26 is a side elevational view thereof.

FIG. 27 is an enlarged front elevational view of a further embodiment of my design.

FIG. 28 is an enlarged cross-sectional view taken on line 28—28 of FIG. 27.

The rear of the light standard is identical to the front. The standard is fragmentarily shown in FIGS. 7 through 22 and 25 through 27 for convenience of illustration, it being understood that in over-all appearance all embodiments are similar to the complete views in FIGS. 1 and 23. The lamps, signs and bottom receptacle shown in broken lines in FIGS. 1, 2, 6 and 8 through 27 are for illustrative purposes only.

I claim:

The ornamental design for a light standard or similar article, as shown and described.
